UNITED STATES PATENT OFFICE.

EDMUND DALY, OF NEW MONTEREY, CALIFORNIA.

DIGGING-TOOL.

1,271,287.

Specification of Letters Patent.

Patented July 2, 1918.

Application filed July 17, 1917. Serial No. 181,101.

To all whom it may concern:

Be it known that I, EDMUND DALY, a citizen of the United States, residing at New Monterey, in the county of Monterey and State of California, have invented certain new and useful Improvements in Digging-Tools, of which the following is a specification.

This invention has relation to digging tools, and has for an object to provide a spade, or combined spade and shovel, constructed and shaped in a manner to permit the digging of a narrow trench to receive water and gas pipes, electric conduits or the like.

Another object of the invention is to provide means whereby my improved digging tool may be mounted on a handle, and adjusted relatively thereto, to vary the angle of the tool as the depth of the trench increases, or according to whether the tool is used for digging or for elevating earth from the bottom of the trench.

In addition to the foregoing, this invention comprehends improvements in the details of construction and arrangement of parts, to be hereinafter described and particularly pointed out in the appended claims.

In the accompanying drawings, in which similar and corresponding parts are designated by the same characters of reference, throughout the several views in which they appear:

Figure 1 is a view in side elevation of a trench digging tool, constructed and formed in accordance with my invention.

Fig. 2 is a view thereof in plan.

Fig. 3 is a view thereof in rear elevation, and

Fig. 4 is a vertical sectional view, taken on the line 4—4 of Fig. 1.

With reference to the drawings, 10 indicates as an entirety the blade of the tool which may be cast or pressed from sheet metal. The blade is extremely narrow as compared to its width, a width of approximately two inches being sufficient for all practical purposes; the width will however depend upon the use to which the tool is to be put. A length of approximately five or six times the width affords a proper proportion in the dimensions.

The outer end of the tool is formed with a straight edge 11, and the tool is curved rearward from said edge with a gradual

curve for about two thirds of its length, whereupon the degree of curvature increases more abruptly so that the inner surface of the rear end of the tool is at approximately 60 right angles to the inner surface thereof at the outer end. The depth of the tool increases from nothing at the edge 11 to the point of greatest curvature where the depth also reaches its maximum as indicated at 12. 65 The depth again decreases toward the rear end where the tool is very shallow. A rib 13 is formed upon the under side of the blade and extended longitudinally thereof as indicated. 70

The rear end of the blade is formed with a pair of spaced, outwardly extending ears 13, formed with apertures to receive a bolt 14 which also passes through a longitudinally extending slot 15 in one end of a 75 handle 16. A wing nut 17 applied to the threaded end of the bolt serves to retain the bolt against displacement and to bind the ears against the handle. The said end of the handle is provided with an axially extending pin 18 which is engaged in any one of a series of vertically spaced openings 19 provided in the rear end of the blade. It will be apparent that by engaging the pin in any one of the openings, the angle of the 80 blade relatively to the handle may be varied, and the slot 15 is provided to permit the pin to be withdrawn from one opening for insertion in the next.

The primary object of my invention is to 90 provide a tool for digging trenches in which to lay pipes, conduits or the like. In accordance with present practice a trench of about twelve inches is dug in which to receive a pipe of from two to three inches in 95 diameter, thus entailing an extra amount of labor in the removal of the earth. A trench of this width is necessitated in view of the width of the shovel used which is about nine inches. My object therefore is to provide a 100 tool which may enable a trench to be dug which will be no wider than the diameter of the pipe or other article to be laid. For this purpose the tool I have disclosed is highly effective. The straight edge on the outer 105 end serves to penetrate the earth, and the sharp corners insure the digging of a trench with straight parallel walls. The tool may furthermore be adjusted so that its lineal dimension coincides more nearly with the 110 axis of the handle when the blade is used for digging; or the angle may be increased

when the blade is used to elevate earth from the bottom of the trench. The long handle, by engaging the walls of the trench, serves to form a guide for the tool to insure the digging of a trench with straight vertical walls.

While I have illustrated and described my invention with some degree of particularity, I realize that many alterations there-
10 in may be made, and I therefore reserve the right and privilege of changing the form of the details of construction, or otherwise altering the arrangement of the correlated parts, without departing from the spirit of
15 the invention or the scope of the appended claims.

Having thus described my invention, what I claim as new and desire to secure by Letters Patent is:

20 1. A digging tool, including a long narrow blade, having a straight chisel edge on its outer end and the blade curved slightly rearward, the curvature increasing toward the rear end until the inner surface of the
25 blade adjacent said rear end is at approximately right angles to the inner surface adjacent the outer end.

Copies of this patent may be obtained for five cents each, by addressing the "Commissioner of Patents, Washington, D. C."

2. A digging tool, including a blade which is long and narrow, curved slightly toward the rear end and having a straight edge at 30 its outer end, the curvature increasing abruptly at the rear end, the blade being also curved transversely, at a maximum adjacent the point of greatest longitudinal curvature, becoming shallower toward both 35 ends.

3. A digging tool, including a blade having a pair of spaced ears and a series of spaced openings in the blade between the ears, a handle pivoted between the ears and having a longitudinal slot through which the pivot extends, and a pin in the end of the handle to enter any one of the openings of the blade to hold the same rigid relative to the handle, the pin being insertible in 40 any one of the openings to vary the angle of the blade.

In testimony whereof I affix my signature in the presence of two witnesses.

EDMUND DALY.
